UNITED STATES PATENT OFFICE.

WILLIAM STAMP, OF SALEM, OHIO.

DOOR-SECURER.

SPECIFICATION forming part of Letters Patent No. 760,933, dated May 24, 1904.

Application filed October 12, 1903. Serial No. 176,782. (No model.)

To all whom it may concern:

Be it known that I, WILLIAM STAMP, a citizen of the United States, residing at Salem, in the county of Columbiana and State of Ohio, 5 have invented a new and useful Door-Securer, of which the following is a specification.

This invention relates to yieldable securing devices for doors, swinging windows, and the like, and has for its object to improve articles of this character and produce a simply-constructed and easily applied and operated device which will hold doors, windows, or other structures with sufficient force to prevent accidental displacement, while at the same 15 time be easily releasable when required.

The invention consists in certain novel features of construction, as hereinafter shown and described, and specified in the claims.

The improved securer may be attached to 20 any construction of door, swinging window, or similar structure exposed to the action of air-currents, which have a tendency to open them or cause them to rattle, but is designed more particularly for attachment to screen- 25 doors and the like and for the purpose of illustration is shown thus applied.

Figure 1 is a transverse sectional view of a portion of a screen-door and the adjacent casing and frame with the improvement applied 30 thereto. Fig. 2 is a front elevation of the improved door-securer. Fig. 3 represents the two parts forming the principal part of the improved holder detached and in perspective.

The improved device consists of two plates 35 10 11 of resilient material, such as sheet-steel, with portions 12 13 bent at right angles to the body portions and reversely curved, forming approximately L-shaped members, with 40 the extremities 14 15 curved in the same direction, as shown, so that when one of the plates 11 is attached to the free edge of the door 16 and the other plate 10 attached to the adjacent portion of the casing or frame 17, 45 with the short arms 12 13 in engagement and the part 14 curving over the part 15, the door will be held closed with sufficient force to resist the action of the wind or any jarring or vibration to which it may be subjected, while 50 at the same time the interengaging and inter-

curving parts will yield to a pulling or pushing force applied to the door. The securer thus constructed will operate automatically when the door is closed, the parts 14 12 yielding to the pressure exerted by the parts 15 55 13, and will also yield readily in the opposite direction when the door is opened, as will be obvious.

The attachment of the device will not mar or disfigure the woodwork of the door or casing, as each piece 10 11 is secured only by 60 screws, as at 18, 19, 20, and 21.

A pull-knob 22 will be secured to the plate 11, adjacent to the set-off portion 13, by the screw 20, and a guard-lug 23 will be likewise 65 secured by the screw 19 adjacent to the set-off portion 12, the knob and lug being both spaced from the parts 12 13 and extending beyond them, so that they serve the twofold purpose of "pull-knobs" to assist in opening 70 the door and likewise as guards to the yieldable catch members to protect them from surrounding objects and also from contact or engagement with the garments of persons passing the door.

The plates can be of any size to adapt them to any size of door or other structure and may be of any required strength and may be plated, japanned, or otherwise coated or protected.

From the foregoing description it will be 80 understood that the device of the present invention embodies a pair of separate members, one of which is designed for application to the free edge of a door and the other to the door-frame. Each of these members is bent 85 from resilient material to constitute an attaching plate or bracket and a spring-arm, the arm 13 of the door member being shorter than the other arm, 12, and bent at its free end into a latch-head 15, lying wholly at the rear side 90 of the arm, and the other arm is bent at its outer free end into a seat or keeper 14, lying wholly upon the front of the arm and disposed to have the latch-head 15 snapped thereinto.

A very important feature of this invention resides in disposing arms 12 and 13 for mutual contact in parallel relation, whereby the maximum frictional engagement is secured between the members, so as to insure a com- 100

paratively rigid interlocking engagement between said members, and thereby obviate rattling of the door. Moreover, by the peculiar disposition of the keeper 14 and the latch-head 15, with the latter wholly upon the rear side of the latch-arm 13, said latch-arm constitutes a striker and initially engages the seat or keeper 14 and gradually presses it laterally out of its normal position, so as to 10 quickly and effectively have the latch-head snap thereinto, and thereby avoid damage to the keeper and keeper-arm.

The short arms 12 13 will preferably be in straight lines for a portion of their distance, as shown, to increase their holding force. 15

Having thus described the invention, what is claimed is—

1. A door-securer consisting of two resilient plates for attachment respectively to the free 20 edge of the door and of the adjacent casing, with their contiguous body portions extending laterally and reversely curved and with their free ends curved in the same direction, and a guard-lug for connection with one of the plates 25 and spaced from the lateral extension therof and also projected beyond the same.

2. A door-securer consisting of two resilient plates for attachment respectively to the free 30 edge of the door and of the adjacent casing with their contiguous body portions extended laterally and reversely curved and with their free ends curved in the same direction and guard-lugs for connection to said plates and 35 spaced from said lateral extensions and extending beyond them, substantially as described.

3. A door-securer comprising separate brackets, the adjacent ends of which are provided with corresponding elastically-yieldable arms projected laterally in the same direction 40 at substantially right angles to the brackets and capable of frictional contact in parallel relation throughout their lengths, the free ends of the arms being provided respectively with mutually-engageable keeper and latch-head members. 45

4. A door-securer comprising separate attaching-brackets, the adjacent ends of which are provided with corresponding elastically-yieldable arms projected laterally in the same

direction and capable of frictional contact in 50 parallel relation, one of the arms being shorter than the other to constitute a latch and provided at its outer end with a head lying wholly at the rear side of the arm, and the other arm being provided at its outer free end with a 55 seat or keeper lying wholly upon the front of the arm and capable of having a latch-head snapped thereinto.

5. A door-securer comprising a frame member and a door member, each of the members 60 being formed from a single resilient plate bent into substantially L shape to form an attaching-plate and a spring-arm, the two arms capable of frictional contact in parallel relation, the arm of the door member being shorter than 65 the other and having its outer free end bowed rearwardly to form a catch-head lying wholly upon the rear side of the arm, and the outer extremity of the other arm being bowed or hooked forwardly to form a seat or keeper 70 disposed to have the catch-head snapped thereinto.

6. A door-securer comprising a frame member and a door member, each of the members being formed from a single resilient plate 75 bent into substantially L shape to form an attaching-plate and a spring-arm, the two arms capable of frictional contact in parallel relation, the arm of the door member being shorter than 80 the other and having its outer free end bowed rearwardly to form a catch-head lying wholly upon the rear side of the arm and the outer extremity of the other arm being bowed or hooked forwardly to form a seat or keeper 85 disposed to have the catch-head snapped thereinto, a guard-lug secured to the attaching-plate of the frame member, and projected beyond the frame thereof, and a pull-knob secured to the attaching-plate of the door member and projected beyond the frame thereof 90 to constitute a guard therefor.

In testimony that I claim the foregoing as my own I have hereto affixed my signature in the presence of two witnesses.

WILLIAM STAMP.
